UNITED STATES PATENT OFFICE.

CHRISTIAN H. T. HAGELSTEIN, OF DORCHESTER, MASSACHUSETTS, ASSIGNOR TO THE
REECE BUTTON HOLE MACHINE COMPANY, OF BOSTON, MASSACHUSETTS, A COR-
PORATION OF MAINE.

BUTTON-ATTACHING MACHINE.

1,077,602.

Specification of Letters Patent.

Patented Nov. 4, 1913.

Application filed October 26, 1912. Serial No. 727,890.

To all whom it may concern:

Be it known that I, CHRISTIAN H. T. HAGELSTEIN, citizen of the United States, residing at Dorchester, in the county of 5 Suffolk and State of Massachusetts, have invented certain new and useful Improvements in Button-Attaching Machines, of which the following is a specification, reference being had therein to the accompanying drawing.

10 My invention relates to button attaching machines and more particularly to that type of machine wherein a plurality of shank-eyed buttons (such as shoe buttons) are sewed successively and at spaced-apart 15 points upon any given article such as a shoe; a prior example of that type of machine which may be referred to for convenience being that illustrated in United States Patent 886,826, patented May 5, 1908.

20 Among the objects of the present improvement are the production of a novel, simple and direct acting machine which may operate at high speed and at the same time will be certain in its operation.

25 Another object is to provide such a machine wherein the entrance of the spreader into the thread loop below the needle is rendered more certain.

30 Another object is to provide in a satisfactory manner an auxiliary member or part adapted to preliminarily enter the thread loop below the needle and hold the same in proper position for the subsequent accurate entry of the spreader.

35 Another object is to provide in such a machine a combined part which serves not only the purpose stated of preliminarily holding open the thread loop, but serves also as a backing member for backing the needle 40 against deflection, bending or breakage during any portion of the operation, such as the spreading of the loop, which imposes a bending strain upon the needle.

45 Further objects and advantages of the present invention will be described herein-after or will be understood by those skilled in the art to which the improvement pertains.

For convenience, I have shown the present 50 improvements as applied to the type of machine illustrated in prior Patent No. 886,826 before referred to, in which type of

machine a primary thread loop is first formed and drawn through the eye of the button, followed by the formation of a secondary loop drawn through the fabric adjacent to the first loop and then interlocked with the first loop by being drawn through it and thereafter spread over the head of the button; the work being automatically fed between the formation of the first and second loop and also between the attachment of the two successive buttons by means of a work feeding mechanism.

To the attainment of the objects hereinabove stated, the present invention consists in the novel arrangements, combinations, parts, and other features illustrated in the drawings or hereafter referred to in the description.

I will first describe one embodiment or employment of the present improvements, and will thereafter point out the novel features in the claims.

In the accompanying drawings forming a part hereof, Figure 1 is a front elevation partly in section of a button sewing machine embodying my present improvements. Fig. 2 shows in left-hand elevation the machine of Fig. 1. Figs. 3 and 4 are partial top views showing the needle bar and spreader bar in cross section and indicating the auxiliary loop opening and needle backing device and its operating cam in two successive positions. Fig. 5 is a partial top view showing the loop spreader and spreader bar. Fig. 6 is a left-elevation showing the needle and the auxiliary part and indicating the spreader position at that stage in the attachment of a button when the secondary loop has been drawn upwardly and the auxiliary part has come into position for backing the needle and for holding open the secondary loop. Fig. 7 is a front view of the same parts and in the same position as indicated in Fig. 6. Figs. 8 to 14 inclusive are views similar to Fig. 6, showing successive positions of the parts referred to up to the complete interlocking of the loops in the attachment of the button. Fig. 15 is a left-hand view of the auxiliary part hereof, detached from the remainder of the machine, while Fig. 16 is a top view, and Fig. 17 is a front view thereof. Fig. 18 is a diagram

illustrating the relative movements of the needle of the spreader, and of the auxiliary part hereinafter referred to.

Similar letters of reference designate corresponding parts in the several figures of the drawing.

I will first describe some of the general machine parts which are not new herein, but are well known in this type of machine. Thus, the base A supports a head A', shown as a hollow casting containing cams, etc., the upper portion of said head being formed into a horizontally extending arm A² which overhangs the sewing position. It should be explained that the work X, which may be a piece of leather, is supposed to be fed from the operator of the machine, that is, toward the left in Figs. 2, 6, and 8 to 14, while the buttons x are sewed thereto by means of the thread y drawn from the usual spool or supply. A work support B, mounted in a standard B', may be yieldingly or otherwise upheld so that the work may be pressed between the support B and the overhanging presser foot C opposed thereto; and any desired means may be employed for causing the separation of the work support and presser foot at the time that the work has to be fed during the process of attaching a row of buttons.

The main shaft Z may be of ordinary arrangement and operation and will have secured upon it substantially all of the operating cams of the machine. At the right-hand end of the main shaft is seen a pulley z, either loose or fast on the shaft and adapted to be continuously driven by a power belt; also a hand wheel z' to facilitate manual operation of the machine. Any ordinary clutch mechanism between pulley z and shaft Z may be employed.

In the machine to which the present improvements are shown as applied, the needle D is of the type having a hook instead of an eye, it passing downwardly through the work from above to the point where the thread mechanism is located, and said hook serving to draw a loop up through the work and through the eye of the button, or through a previous loop as the case may be. The needle D is shown secured at the lower end of a needle bar D', which is fitted to slide vertically in the arm A², and said needle may be reciprocated in any desired manner, for example, through bell crank d', Fig. 1, link d², and arm d³, the latter having a pin which engages in the cam slot of cam d⁴ mounted on the main shaft Z. It will be understood that the presser foot C is apertured or slotted at e, which permits the passage of the needle and attached buttons therethrough.

For feeding along the work any convenient means may be employed, such, for example, as the feeding prong shown in

Patent No. 886,826, but as the work feeding mechanism *per se* forms no part of the present invention, the same for convenience is omitted herefrom. Similarly, any desired construction of thread mechanism may be employed, and as that, *per se*, forms no part hereof, it is not completely shown, although a looper bar F is indicated, carrying a looper f at its upper end, said looper being adapted to swing at proper times to carry the thread into the needle hook. The loop spreader G is mounted and actuated to co-operate with the other parts and its details will be hereinafter described. Similarly, a proper cast-off to co-operate with the hook needle will be understood, this being completely shown in the Patent No. 886,826 referred to; but as the cast-off would confuse the drawings illustrating the present improvement, the same is for convenience omitted from several figures, and is broken off in Figs. 1 and 2. Where shown, it is indicated by reference H and the oscillating cast-off bar by reference H'. Button feeding mechanism will be understood and it will be of a nature to feed buttons one at a time into proper relation to the needle for the attachment successively of the buttons at spaced-apart points on the work. For clearness, the button feeding mechanism is entirely omitted. The contour and therefore the timing of all of the cams herein described will be such as to cause the different instrumentalities to harmoniously co-operate for forming the thread loops and interlocking them with the buttons into attaching knots.

I will now describe the features to which, more particularly, claim of novelty is herein made and explain their co-operation with the other parts of the machine.

The loop spreader G, while it may take various forms, is shown as of the form indicated in Fig. 1 in front view, Fig. 2 in left view, and Fig. 5 in top view enlarged. The spreader is carried at the foot of a vertical axle or spreader bar G', capable of sufficient oscillation to permit the swing of the spreader in a horizontal plane inward to spreading position and outward to withdrawn position. The spreader is not mounted directly upon the spreader bar, but upon a short axle contained in a horizontal sleeve g, so that the spreader point g' can be tipped down at the proper time for shedding the thread loop over the button head. The sleeve g² holds the spreader axle in place and also serves for the attachment of spring g³, whose tendency is to hold the spreader in a horizontal position. The spreader point g' is so located that when the spreader bar is swung the spreader point will pass as near as may be directly between the two strands of thread forming the secondary loop held by the elevated needle. Any suit-

able means may be employed for oscillating the spreader bar from its upper end, but the details of this will be omitted as forming no part, *per se*, of the present invention.

5 Attention, however, is called to the cam groove g^1 , from which is effected the actuation of the train of mechanism which oscillates the spreader bar and swings the spreader. For effecting the down tipping 10 of the spreader point at the proper time for shedding the loop over the button, a finger or projection K may be employed, this being formed as a part of the spreader. When the spreader has been swung completely inward, the finger K comes beneath the end k of a swinging arm k' pivoted at k^2 to a fixed lug k^3 , while at the other end of arm k' is provided a pivotal connection k^4 to an upwardly extending link k^5 by which the 15 arm k' may be swung to depress the finger K . The further connections between the link k^5 and the cam k^1 on the shaft Z are omitted, as constituting, *per se*, no part of the present improvements.

20 25 The mechanism so far described might be employable for the attachment of buttons in the mode referred to. It has been found, however, that there is an uncertainty in the operation of a machine having only such described mechanism, in that frequently the spreader will not accurately enter and spread the secondary loop, with the result that a defective knot or attachment is produced, which at least would require the 25 stoppage of the machine, its reversal and a re-operation, while if not detected, the shoe or article under operation might be allowed to proceed, and when taken from the machine would be so defective as to require a great loss of time in correcting the omission.

The hooked needle in rising to draw the secondary loop through the work holds the loop open into a sort of thread-eye of only very narrow breadth, equal at the most to 30 the diameter of the needle, and tapering to a smaller width by the approach of the two thread strands which meet at or above the work. In machines of this type the needle is preferably elevated to a point considerably above the level of the spreader's operation, so that the spreader does not get the advantage of the full width of the thread-eye, but must enter the same at a point of smaller width. In addition to this difficulty, 35 it is also the fact that any slight displacement of the thread loop in any manner, whether at the lower end or whether by the deformation or displacement of the needle, will increase the inaccuracy of the spreader's 40 operation. Moreover, the spreader that has been found of best utility in such machine is one having a comparatively broad nose or point as shown, which decreases its ability to accurately enter the thread-eye, and any 45 slight wear or displacement of the spreader

would increase the difficulty. For these and other reasons, it has been found, as stated, that the spreader occasionally misses the thread-eye, with the time-consuming and therefore expensive results noted.

According to the present improvement, the difficulties referred to are overcome by the combination of the needle, spreader, and other parts referred to with an auxiliary or supplemental part, which may be termed a loop engager, which is adapted to engage in the eye of the thread loop carried by the needle and to hold it in condition for the spreader to subsequently enter. This loop engager not only preserves the thread-eye produced by the needle's diameter and holds the same open to its full width at the level of the engager, notwithstanding the further elevation of the needle, but the engager also properly positions the loop in a predetermined position wherein the spreader is bound to accurately enter; and where desired, the loop engager may be caused to somewhat enlarge the thread-eye by wedging it open in advance of the entry of the spreader.

The supplemental part or loop engager L hereof is shown separately in Figs. 15 to 17 and is indicated in operative position in Figs. 6 and 7. Actually, it is the forward pointed tip M of the part L which engages in and holds and positions the thread-eye. Indeed, as will appear, the part L may be considered a combined part serving not only to engage the thread-eye through the tip M , but also to back up or support the needle through the needle backing portion N thereof. The combined part L is shown partly in dotted lines in Fig. 2, where it is seen to be pivoted at l to a fixed part of the head A^2 , the pivot being horizontal so that the part L may swing in a vertical plane, its lower extremity swinging forwardly and backwardly according to its actuation.

In order to keep the part L normally in the position indicated in Figs. 2 and 10, it is provided with a rearward extension l' , to which is secured a spring l^2 , Fig. 2, tending to pull upwardly on the projection l' . For causing the movement of the part L against the resistance of the spring l^2 , the arrangement shown in Figs. 3 and 4 may be employed. These show, laterally projecting at one side of the part L a lug l^3 which is properly shaped to coöperate with a cam l^4 secured upon the vertical spreader bar G' . By such arrangement, the inswinging of the spreader by the oscillation of the bar G' is accompanied by the co-action between cam l^4 and lug l^3 for swinging forwardly the part L from the position of Figs. 3 and 13 to the position of Figs. 4 and 6. It should be stated that the cam l^4 , which is shown adjustable, is timed to bring the part L to its forward position slightly in ad-

vance of the entry of the spreader into the thread-eye. The loop engaging tip M, and the needle backing surface N of the part L are shown located at the lower extremity of 5 the downwardly extending arm L' of the latter, so that they will have adequate forward and rearward movement to enable them to come to the operative position of Figs. 4 and 6 in the forward movement, and 10 to withdraw in the rearward movement to the inoperative position of Figs. 3 and 13, where the needle bar may pass the part L, as seen in Fig. 14, without interference.

In the operative position of the part L, 15 as seen in Figs. 4, 6, and 7, the loop engaging tip M has entered the thread-eye just below the needle, as the latter is ascending, and has even slightly widened the eye preparatory to the entrance of the spreader therein, while 20 the needle backing surface N has been brought into actual contact with the needle so as to positively hold the needle against the rear side to prevent rearward deflection of the needle at the time the spreader enters 25 the thread-eye for opening it and tipping it rearwardly over the button. As shown in the several figures, the tip M is perforated at m by a hole sufficiently large to admit 30 the needle's passage, for a purpose that will hereinafter appear.

Having thus indicated in a general way the purpose and arrangement of the needle, the spreader, the loop engager, and the needle backer, I will now proceed to describe 35 in detail the preferred operation of the parts in attaching a button. In such description reference will be had not to the actual contours of the operating cams, but to the diagram thereof shown in Fig. 18 40 and to the actual positions of the parts in Figs. 6 to 14, from which those skilled in the art will be enabled to readily design the cams and operating connections.

For the attachment of each button, the 45 needle first descends and penetrates the fabric. At O in the diagram, Fig. 18, the needle is shown descending. The full line indicates the needle movements, the left incline referring to a down movement, and vice versa. 50 The dotted line in the diagram refers to the spreader movement, a right-hand incline indicating an inward swinging, and vice versa. The broken, or dot and dash line indicates the movement of the part L, a left incline 55 referring to a forward swinging, and vice versa. At the point 2, the needle has reached its lowest position beneath the fabric, where it pauses while the looper feeds the thread loop thereto. The needle next ascends to its 60 highest position indicated at point 5 in the diagram, it having then drawn a thread loop through the work and through the button-eye. Thereupon the needle again descends, this time through the first loop and 65 through the work to the lowest position as

indicated at point 8, where the looper feeds the secondary thread loop to the needle. Thereupon, about point 9 the needle again rises until it attains its highest position. About the point 9 it will also be seen the 70 spreader and the part L commence to move. The part L reaches its forward position at the point 10, of the diagram before the spreader is completely swung inward and while the needle is still rising. This stage 75 of the parts is shown in Figs. 6 and 7. The part L is forward, thus backing up the needle and engaging the thread loop; the needle has not finished rising; the spreader has not yet entered the loop. At point 10.5 the 80 needle has reached its highest position and the spreader has been swung completely inward, thus entering the properly positioned thread-eye. This stage is indicated in Fig. 8 and is maintained on the diagram to point 85 12. Thereupon, the needle dips, passing through aperture m of the engager M and also through the open center of the spreader. This movement is for the purpose of disengaging the loop from the needle and putting 90 it upon the spreader in a manner well understood. It is also understood that the needle cast-off co-operates in this operation by remaining elevated during the needle's descent, so as to uncover the needle's hook and permit the casting off of the loop. To facilitate the casting off of the loop, the spreader 95 slightly withdraws, as indicated. Figs. 9, 10 and 11 indicate these operations, the needle having dipped in Fig. 9, the spreader 100 withdrawn slightly in Fig. 10, and the needle having risen in Fig. 11. The spreader has thus taken possession of the thread loop. The spreader thereupon again swings inwardly to its full extent and is tipped downwardly, thus shedding the loop over the button, as indicated in Fig. 12, this operation being completed at point 16 on the diagram. Thereupon, the spreader swings 105 completely outward to withdrawn position, and simultaneously the part L swings downwardly to withdrawn position, as indicated between 16 and 17 on the diagram. This completes the attachment of the button, save for the taking up of the thread to tighten the 110 knot, and in this stage the parts will stand as indicated in Fig. 13. Thereafter, it will be understood that the work is fed for a distance between two buttons and the needle again descends from point 19 on the diagram 115 to point 2 to its lowest indicated position in Fig. 14.

The utility of the loop engager M is indicated principally in Figs. 6, 7, and 8, showing the loop to be properly maintained 120 and also positioned, and in fact, slightly spread so as to insure that the spreader in every operation will properly enter the thread loop or eye. The utility of the needle backer M is indicated in the same 125 130

figure, the needle backer serving to prevent the distortion and other injury to the needle due to the rearward pull caused by the rearward movement of the spreader 5 in entering the thread loop, as in Fig. 8; which, but for the backing up of the needle, would cause slight distortion or strain such that when repeated many thousands of times would eventually distort or 10 break the needle, or by its distortion cause conflict with other parts, unreliable operation, and perhaps serious breakage.

The loop engager being a part separate and distinct from the spreader may be accurately calculated in its movements irrespective of the various spreader operations. For example, the loop engager may be timed to enter the thread-eye, as stated, immediately beneath the needle point as the needle 20 ascends, thus taking advantage of the full width of the thread-eye. The loop engager can be given the most effective shape to serve this function. It will be noticed that the engager's upper surface is inclined 25 downwardly so as to prevent the accidental catching of the thread loop thereupon, thus insuring the delivery of the thread loop, as seen in Fig. 10, to the spreader. It will also be noticed that, referring to the parts 30 as seen in Fig. 6, the member L, when moved to the right to its operative position, gives to the needle a backing in a right-hand direction against deflection in an opposite or left-hand direction, and that the tip of said 35 member enters the thread loop on the needle in the same direction as such backing, namely, in a right-hand direction. The contacting of the needle, as shown, is along the same line as that in which both the work 40 feed and the spreader operate, although in an opposite direction.

By the above-described mechanism, it will be seen that the objects and advantages referred to are attained, and other advantages 45 will be apparent to those skilled in the art. Since many specific matters of arrangement, form, combination, and detail may be varied indefinitely, it is intended not to restrict the statement of the present invention there- 50 to, excepting as may be set forth in the appended claims.

What I claim and desire to secure by Letters Patent is:

1. A machine for attaching by thread to the work buttons or like articles, including 55 in combination, a reciprocable loop forming needle, a combined needle backing and loop engaging member adapted to be intermittently moved to the needle to give it backing 60 ing in a given direction against opposite deflection, and means to move said member to the needle to cause it to give such backing and to enter the thread loop on said needle in the same direction as said backing.

65 2. A machine for attaching by thread to

the work buttons or like articles, including in combination, a reciprocable loop forming needle, a combined needle backing and loop engaging member adapted to be intermittently moved to the needle to give it backing 70 in a given direction against opposite deflection, and means to move said member to the needle to cause it to give such backing and to enter the thread loop on said needle in the same direction as said backing, and means for relatively advancing the work 75 while the loop is on the needle in a direction opposite to said backing.

3. A machine for attaching by thread to the work buttons or like articles, including 80 in combination, a reciprocable loop forming needle, a combined needle backing and loop engaging member adapted to be intermittently moved to the needle to give it backing 85 in a given direction against opposite deflection, a spreader adapted to enter a thread loop while the loop is still engaged upon the needle and to spread the loop over a button, and means to move said member to the needle in advance of the spreader's 90 operation to cause it to give such backing and to enter the thread loop on said needle in the same direction as said backing.

4. A machine for attaching by thread to the work buttons or like articles, including 95 in combination, a reciprocable loop forming needle, a combined needle backing and loop engaging member adapted to be intermittently moved to the needle to give it backing 100 in a given direction against opposite deflection, a spreader adapted to enter a thread loop while the loop is still engaged upon the needle and to spread the loop over a button, means to move said member to the needle in advance of the spreader's operation to cause 105 it to give such backing and to enter the thread loop on said needle, and means for causing the spreader to enter the loop oppositely to said backing after said member has engaged a loop but before the needle and 110 loop are disengaged.

5. A machine for attaching by thread to the work buttons or like articles, including 115 in combination, a reciprocable loop forming needle, a combined needle backing and loop engaging member adapted to be intermittently moved to the needle to give it backing 120 in a given direction against opposite deflection, a spreader adapted to enter a thread loop while the loop is still engaged upon the needle and to spread the loop over a button, means to move said member to the needle in advance of the spreader's operation to cause it to give such backing and to enter the thread loop on said needle in the 125 same direction as said backing, and means to operate the spreader while both said member and the needle are engaged with the loop to enter the loop oppositely to the aforesaid given direction.

6. A machine for attaching by thread to the work buttons or like articles, including in combination, a reciprocable loop forming needle, a combined needle backing and loop engaging member adapted to be intermittently moved to the needle to give it backing in a given direction against opposite deflection, a spreader adapted to enter a thread loop while the loop is still engaged 5 upon the needle and to spread the loop over a button, means to move said member to the needle in advance of the spreader's operation to cause it to give such backing and to enter the thread loop on said needle in the same direction as said backing, and means to operate the spreader while both said member and the needle are engaged with the loop to enter the loop oppositely to the aforesaid given direction; said combined member 10 comprising a needle backing surface and a loop engaging tip formed directly at said surface.
7. A machine for attaching by thread to the work buttons or like articles, including 25 in combination, a reciprocable loop forming needle, a combined needle backing and loop engaging member adapted to be intermitt-

tently moved to the needle to give it backing in a given direction against opposite deflection, a spreader adapted to enter a thread 30 loop while the loop is still engaged upon the needle and to spread the loop over a button, means to move said member to the needle in advance of the spreader's operation to cause it to give such backing and to enter the 35 thread loop on said needle in the same direction as said backing, and means to operate the spreader while both said member and the needle are engaged with the loop to enter the loop oppositely to the aforesaid 40 given direction; said combined member comprising a needle backing surface and an apertured loop engaging tip formed directly at said surface, and said needle having actuating means causing it to dip into the aperture of said member for shedding its loop 45 upon the spreader.

In testimony whereof I affix my signature in presence of two witnesses.

CHRISTIAN H. T. HAGELSTEIN.
